TRAFFIC SIGNALING SYSTEM AND APPARATUS

Howard H. Bell, Schenectady, N. Y., assignor to
General Electric Company, a corporation of
New York

Application October 1, 1932, Serial No. 635,776

5 Claims. (Cl. 177—337)

My invention relates to signaling systems and apparatus and more particularly to automatic traffic signaling circuits.

In many traffic signaling systems, now in use, individual timing units are used to regulate the signals at each street intersection. The timers are all kept in synchronism and may be operated so that the "Go", "Stop" and "Caution" signals operate in unison, or at certain timed relations, with each other. In either of these two systems of operation, which are often referred to as the "non-progression" or "progression" systems, respectively, it is desirable at certain times to extend the green or "Go" period beyond the normal length of time, along any one street, in order to enable the increased traffic to flow rapidly through that street.

It is the main object of my invention to provide apparatus whereby such green or "Go" period may be extended in either a progression or a non-progression system at any predetermined time of day or during any predetermined number of cycles of operation.

My invention will be better understood from the following description when considered in connection with the accompanying drawing and its scope will be pointed out in the appended claims.

The single figure in the drawing illustrates diagrammatically a system of traffic control embodying my invention. The system as illustrated, includes a program device 10, a master timing unit 11, and individual signal units 12, of which two are shown connected to the common energy source indicated by conductors 13 and 14.

Each unit 12 includes a driving motor 16 and switching means 17 to operate the signals 18 in a predetermined sequence. The signals 18 are indicated as two groups of three signal lights each, indicating one set for the main street traffic and another for the cross-street traffic. The lights are marked "G", "A" and "R" meaning green, amber and red respectively. The motor 16 drives the switching mechanism 17 through shaft 19 and releasable clutch 20 which is operable by electromagnet 21. The energization of magnet 21 is controlled by a cam 22 mounted on shaft 19 and switch 23 whose contact 24 engages contact 25 only when the nose 27, of the supporting spring 29 for contact 25, falls into groove 28 of the cam 22.

The master timer 11 is driven by a motor 30 through shaft 31, and a clutch 32 operated by an electromagnet 33. Upon the shaft 31 a cam 22' is mounted and provided with a groove 28', both corresponding to cams 22 and grooves 28 respec-

tively. The cam 22' of the master timer operates a double throw switch 35 of which main contact 36 is mounted on a spring 31, the nose 37' of which slides on the surface of cam 22'. The contact 36 normally engages a contact 38, but engages a contact 40 when the nose 37' has fallen into groove 28.

The operating magnet 33 of the master timer clutch 32 is controlled by the switch 35, by a time delay relay 42 and program device 10. The relay 42 comprises a driving motor 43 of which the armature 43' drives a worm 44 mounted on shaft 45. One end of shaft 45 is mounted in arm 46' of a bell-crank 46 which is pivoted at 47 and may be rotated by a magnet 48. When this magnet is energized, it attracts arm 46'' and thereby lowers arm 46' which carries the end of the worm shaft 45. The magnet 48 and the winding of motor 43 are connected in series and are always energized and deenergized simultaneously. When, therefore, the worm 44 is lowered, it is also rotated, and thereby drives a wheel 50 which it engages only when in the lowered position. The wheel 50 is mounted to rotate freely about a shaft 51 being connected thereto only by a spiral spring 52. The spring 52 is arranged to return the wheel 50 to its starting position every time the worm 44 is moved out of engagement with the wheel 50. The starting position of the wheel 50 is determined by an adjustable stop 53 against which a pin 54, mounted in the wheel 50, comes to rest. The position of the adjustable stop determines the timing of the relay as will hereinafter be explained.

Upon rotation of the wheel 50 the pin 54 rotates in a clockwise direction until it engages and trips a pivoted latch 56. The tripping of the latch 56 permits a spring 57, which is attached to the bell-crank 46 and which is placed under tension when the worm 44 is brought into engagement with the wheel 50, to move a pivoted contact member 55 and thereby break a circuit between the contacts 56 and 55 and through the relay 42 as will be hereinafter explained.

The program device 10 is provided with two or more arms 60 and 61 which may be set to any desired position and their effect is to close a circuit between the relay 42, specifically contact 55, and the source of energy, or conductor 13, during predetermined periods of the day.

In operation, the cams 22 periodically close switches 23 which energizes clutch magnets 21, the circuit being, conductors 13 and 65, magnet 21, switch 23, common conductor 66, contacts 38, and 36, conductor 67 back to line 14. If, 55

therefore, this circuit is completed the magnet 21 opens the clutch 20 and thereby stops the signal mechanism 17 and keeps it stopped until the circuit through the magnet is broken.

- 6 The master timer 11, meanwhile also moves corresponding cam 22' and when the groove 28' reaches the position corresponding to that of the grooves 28 the contacts 36 and 38 separate and the circuit to the clutch magnets 21 is broken.
- 10 The speed of rotation and the shape of the cams are so arranged that the individual timers are started and open switches 23 before the master timer again closes its contacts 36 and 38. The clutch magnets 21 are thereby deenergized, the 15 clutches 20 are closed, and the cams 22 moved sufficiently to open the switches 23 before the clutch magnet circuits are again closed at contacts 36 and 38. It is therefore evident that in 20 this system the cams 22 cannot pass the circuit closing position of switches 23 until the master opens the clutch circuits. The signals 17 are thereby maintained in synchronism with the master timer.

For the sake of carrying out my invention, it 25 is desirable to repeat the synchronizing action once during each cycle of operation and when the signals are operated in progression, that is, a certain time relation between the starting instants of the various signals exists, to select an instant 30 in which all the signals on the system are green or indicate that signal which it is desired to temporarily increase during that cycle.

The extension of a green signal, in accordance 35 with my invention is obtained by the use of the program device 11 and time delay relay 42 as follows: The master timer switch 35 is a double throw switch. When it opens its contacts, 36 and 38, it simultaneously closes its contacts 36 and 40. This closes a circuit from line conductor 14 40 through conductor 67, contacts 36 and 40, conductor 68, and clutch magnet 33. Clutch magnet 33 is connected in multiple with the winding of motor 43 and operating magnet 48 by conductors 69 and 70; the magnet 48 and motor 43 being 45 in series with each other through conductor 11. This circuit is completed to the other line conductor 13 through conductor 72, contacts 56 and 55, conductor 73, program device 10 and conductor 74.

50 During that part of the day in which the program device closes the circuit through itself, the circuit through the clutch magnet 33, coil 48 and motor 43 is closed every time the contacts 36 and 40 engage. The magnet 33 then opens clutch 32 55 and thereby stops rotation of the cam 22'. The energization of the coil 48 and the motor 43 starts wheel 50 rotating for a period determined by the angular distance between the pin 54 and the clutch 56 which is obtained by the adjustment 60 of stop 53. When wheel 50 has moved pin 54 into engagement with latch 56 the spring 57 separates the contacts 55 and 56 thereby opening the circuit through clutch coil 33, the operating coil 48 and motor 43 of the relay 42. The worm 65 44 is moved out of engagement with wheel 50 and contact 55 again moves into engagement with contact 56 and latch 50. The apparatus is then again ready for operation during the following cycles of operation, until the program device 70 breaks the circuit.

During normal operation of the system the master cam 22' rotates continuously and breaks the clutch circuits for the individual timers only long enough for them to restart and break the 75 same circuit by opening the switches 23. When

the master timer is therefore stopped in that position, in which it breaks the timer clutch circuits and closes its own clutch circuit due to the program switch being closed, it is necessary to provide means to maintain the individual timer clutch circuits closed. For this purpose a contact 75 is provided on the core 33' of the master clutch coil 33. This contact 75 is arranged to engage contacts 76 and 77, which are attached to conductors 66 and 67 respectively, only when the clutch coil 33 is energized and the master timer therefore stopped. The circuit through contact 75 provides a shunt across the synchronizing contacts 36 and 38 and thereby the synchronization period, which is normally only momentary, is lengthened by that period during which the master timer is stopped.

It is therefore clear that in the above-described system, with the apparatus described, it is possible to select any particular signal and prolong 20 it for a predetermined period, as determined by the adjustment of the time delay relay, during any number of cycles of operation occurring during predetermined parts of the day.

What I claim as new and desire to secure by 25 Letters Patent of the United States, is:

1. In a traffic control system, the combination of a plurality of signaling units provided respectively with a series of corresponding signals, means located in each unit for continuously 30 operating said signals in a predetermined sequence, means for synchronizing said units including means for periodically stopping the operating means for each unit, means for restarting each unit only when said units are in synchronization, and means for delaying the operation of the restarting means for a predetermined period of time at preselected ones of said restarting operations.

2. In a traffic control system, the combination 40 of a plurality of signaling units provided respectively with green, amber and red signals, means for operating the signals in sequence and in recurring cycles including a switching mechanism, a motor, and an electrically operated clutch between the motor and said mechanism, an operating circuit therefor, means for synchronizing said motors including a master controller, provided with a cam, a corresponding cam operated by each of said units respectively, a switch on each unit operated by its respective cam for closing the circuit to the clutch in said unit and a switch cooperating with said master cam for breaking the clutch circuits of said units, and means for periodically stopping said master cam 55 and unit cams including a program device for determining the cycles of operation during which the cam should be stopped, and a time delay relay in series with said program device for determining the length of said stop period.

3. In a traffic control system, the combination of a series of traffic signaling units operable through a signaling cycle, means for operating said units individually, means for stopping said operating means at a predetermined instant in each cycle, a master timer arranged to restart said units simultaneously and thereby synchronize said operating means, and means for delaying the operation of said master timer a predetermined time at each of the preselected series of 65 70 said synchronizing operations.

4. In a traffic signaling system, the combination of a series of signaling units, each unit having a series of signals corresponding respectively to signals in the other units, means for operating 75

- the signals in each unit in a predetermined cycle, means for operating corresponding signals in a predetermined time relation with respect to each other, means for periodically synchronizing said
- 5 signal operating means including means for stopping said operating means at a predetermined instant in the operating cycle, and means for simultaneously restarting the said operating means of each of said series of units, and means
- 10 including a program device for delaying the operation of said starting means for a predetermined length of time during predetermined operating cycles whereby the time of the signal indicated by each unit during the synchronizing operation is
- 15 correspondingly extended.
5. In a traffic control system, a plurality of sign-
- aling units provided respectively with a series of corresponding signals, means for operating said signals in a predetermined cycle, means for stopping said operating means at a predetermined instant in each operating cycle, a master timer for simultaneously restarting said operating means of each of said plurality of units, and means for controlling said master controller comprising a normally inactive time delay relay for delaying said restarting operations a predetermined time interval respectively and a program device for effecting operation of said relay during the predetermined restarting operations which are to be delayed.
